UNITED STATES PATENT OFFICE.

LAWRENCE C. KARCHER AND LIONEL ASMAN, OF EVANSVILLE, INDIANA.

AUTOMOBILE HEATER.

Application filed December 12, 1924, Serial No. 755,473. Renewed November 26, 1926.

This invention relates to those automobile heaters which utilize the heat of the exhaust gases for heating air and delivering the heated air to the interior of the car.

5 The object of the invention is the provision of an improved heater of the class described which will be adapted for application to the exhaust pipe leading from the exhaust manifold and so constructed and arranged that heated air may be delivered to a suitable register in the floor of the car.

Our improved heater embodies a drum or shell adapted to be slipped over the exhaust pipe after the latter has been disconnected from the manifold, and provided with novel means for securing the drum to the exhaust pipe and also having an outlet pipe adapted to be inserted in a hole in the floor board of the car to deliver the heated air to any 20 suitable register provided for its control.

Our heater possesses several advantages, due to its improved construction, among which are simplicity, cheapness of manufacture, ease of installation, adaptability to 25 deliver a relatively large volume of heated air due to the construction and manner of operation of the heater, and adaptability to be easily disconnected from the floor of the car and reversed so that the heat will be directed downwardly and not into the car during 30 warm weather, without the necessity of detaching the exhaust pipe.

The foregoing, and other, advantages appear more fully from the following description 35 of a practical embodiment of the invention which is shown in the accompanying drawings, in which:

Figure 1 is a side elevation showing the heater applied to the exhaust pipe of an 40 automobile engine and to the floor board of the car.

Fig. 2 is an end elevation of the left hand 45 end of the heater, Fig. 1; and

Fig. 3 is a section on line 3—3, Fig. 1.

A part of the exhaust manifold of an automobile such, for instance, as a "Ford", is shown at 1, the exhaust pipe appearing at 2, the two being connected by the usual packing nut 3.

50 Our heater, instead of being connected to the manifold 1 as has been heretofore proposed, surrounds and is connected to the exhaust pipe 2 for the reason that this position so locates the heater that it will be adapted 55 to deliver the heat through the floor of the car instead of through the dash or front of

the body thereof, and for the further reason that a heater connected to the exhaust pipe may be readily attached.

Our heater has a cylinder, shell, or drum 60 4 which is wholly open at its forward end 5. At its rearward end the drum 4 carries a novel clamp 6 by which the drum or shell 4 is secured to the exhaust pipe and which prevents escape of the air at said rearward end 65 and insures the upward flow of the air through the outlet pipe 7 which passes through the floor board 8 of the car and is provided with a suitable register 9 by which the flow of the heat into the car may be 70 controlled.

The drum or shell 4 is of any suitable sheet metal, being preferably of cylindrical form; the outlet pipe 7 is riveted or spot 75 welded to the drum 4, as shown at 10.

The clamp 6 may be modified from the construction shown according to the car on which the heater is to be used. The clamp will be provided with a flange when used on cars other than Fords to afford a better 80 clamping action on the pipe 2 of such cars.

The clamp 6 comprises two sections 11, 12, one of which, 11, is spot welded or riveted to the end of the drum 4 at different points, as shown at 13. The other section, 12, is 85 pivoted at 14 on a loose rivet to section 11 so that it can be swung open or closed in relation to the section 11. Like the section 11, section 12 has a flange 15 which overlaps the end of the drum 4. Ears 16 and 17 on 90 sections 11 and 12, respectively, are connected by a screw and nut fastening 18 by which the sections 11 and 12 may be drawn tightly against the exhaust pipe 2 to assist in holding the drum on said pipe. The reception of the end of the outlet 7 in the hole in the floor board 8, in connection with the engagement of the clamp 6 with the pipe 2, securely holds the heater in position.

To apply the heater, the packing nut 3 100 is loosened, enabling the pipe 2 to be moved sidewise sufficiently to enable the heater to be passed thereover until it is in proper position. The outlet 7 is then fitted in a suitable hole in the floor board 8, the register 9 applied and the clamp 6 tightened on the exhaust pipe. The heat from the exhaust pipe causes the air inside the drum 4 to be heated and to rise through the outlet 7. When the car is in motion, the outer air 110 drawn in and forced into the drum 4 at its forward end 5 insures an increased volume

of air supplied to the register 9, this air being heated by radiation from pipe 2 as it flows through the drum and outlet to the register.

5 In warm seasons when the heater is not needed, the clamp 6 is loosened, the outlet 7 pulled out of the hole in the floor board 8 and the heater completely reversed in position so that the outlet 7 will point downwardly instead of upwardly. The clamp 6 is then tightened. Thus, without having to remove the heater from the exhaust pipe, the heat is directed downwardly below the car and does not have access to the interior 10 of the car. When cool weather arrives, it is a simple matter to turn the heater back to its former position and re-insert the outlet 7 in the hole in the floor board 8.

We are aware that modifications may be 20 resorted to without departing from the spirit of the invention.

We claim:

The combination with the exhaust pipe of an automobile engine, of an automobile 25 heater comprising a drum or shell which

surrounds said exhaust pipe, is open at its front end, and carries on its side near its rear end an outlet pipe for the delivery of the heated air to an opening in the floor-board of the automobile, said drum or shell being 30 provided at its rear end with a clamp composed of substantially similar arc-shaped sections adapted, collectively, to surround and engage the exhaust pipe, each of said sections having a flange overlapping the end 35 of the drum, the flange of one of said sections being secured to the drum, the other section being hinged to the fixed section aforesaid, ears carried by said sections, bolt and nut means connecting the ears for 40 clamping the movable section around and against the end of the drum and around and on the exhaust pipe of the engine, said sections closing the rear end of the drum, said drum being internally larger than the exhaust pipe.

In testimony whereof we affix our signatures.

LAWRENCE C. KARCHER.
LIONEL ASMAN.
